The ornamental design for a cigarette box, as shown and described.

DESCRIPTION

FIG. 1 is a plan view of a cigarette box showing my new design in a flat, blank configuration;

FIG. 2 is rear perspective view of the cigarette box showing my new design in an assembled and collapsed configuration;

FIG. 3 is a top end view thereof;

FIG. 4 is a rear elevation view thereof;

FIG. 5 is a bottom end view thereof;

FIG. 6 is a side elevation view thereof;

FIG. 7 is a front elevation view thereof;

FIG. 8 is a rear perspective view of the cigarette box showing my new design in an assembled and open configuration;

FIG. 9 is a top end view thereof;

FIG. 10 is a rear elevation view thereof;

FIG. 11 is a bottom elevation view thereof;

FIG. 12 is a front elevation view thereof; and,

FIG. 13 is a side elevation view thereof.

The broken lines in FIGS. 1–13 are perforations and form no part of the design.
